UNITED STATES PATENT OFFICE

2,232,816

ELECTRIC LAMP

Irving H. Van Horn, East Cleveland, Ohio, assignor to General Electric Company, a corporation of New York

Application January 19, 1940, Serial No. 314,640

5 Claims. (CL 176—34)

My invention relates in general to electric incandescent lamps comprising a sealed bulb containing a filament adapted to operate at a high temperature. More particularly, my invention relates to a heat protective arrangement for such lamps.

In the operation of electric incandescent lamps of the high wattage type, various parts of the lamp, such as the bulb wall, stem, and the base, are heated to very high temperatures by the heat radiated by the filament. This is particularly true in reflecting incandescent lamps of the type in which the side wall portion of the bulb is formed as a reflecting surface and the high-wattage filament is mounted in relatively close relation to that portion of the bulb wall adjacent the bulk neck, such a filament location being necessitated by optical requirements. When such lamps are burned in a base-up position, the neck and adjacent portions of the bulb wall are apt to be heated to such a high temperature as to cause a cracking of the glass. Furthermore, the excessive heat in the neck portion of the bulb may prove to be injurious to the lamp base and in some cases even to the lamp socket.

One object of my invention is to provide an electric incandescent lamp with a heat protecting device for shielding the bulb neck and lamp base from the heat radiated by the lamp filament.

Another object of my invention is to provide an electric incandescent lamp with a combined heat protecting and blackening collector device.

Still another object of my invention is to provide a relatively high-wattage reflecting type incandescent lamp employing a relatively small sized envelope.

A feature of the invention is the provision of a disc of insulating material in the neck of the bulb between the lamp stem and the filament together with a wire screen element of cylindrical shape secured to the periphery of the insulating disc and extending longitudinally of the bulb neck to a point a relatively slight distance below the filament.

Further objects and advantages of my invention will appear from the following detailed description of a species thereof and from the accompanying drawing in which:

Fig. 1 is an elevation, partly in section, of an electric incandescent lamp comprising my invention; and Fig. 2 is a perspective view of the lamp mount only showing the heat protective device comprising my invention in place thereon.

Referring to the drawing, the lamp according to the invention comprises a hermetically sealed

bulb 10 containing a gas filling such as nitrogen, argon or other suitable gas, and having a neck portion 11 and a base 12 secured to said neck portion. The base may be of the conventional screw-threaded or any other suitable type. The bulb proper is formed with a flattened top portion 13 having a curvature of relatively large radius and a reflecting side wall portion 14 shaped to conform to a surface of any desired optical reflecting shape such as, for instance, a paraboloid. This side wall portion 14 is provided, preferably on its inner surface, with a coating 15 of suitable reflecting material such as aluminum. The coating 15 extends from a point adjacent the junction of the side and top walls 13 and 14 down to the bulb neck 11 and continuing for a short distance along the said neck. The flattened top portion 13 is left clear for the transmission of the light rays therethrough. The inner surface of the bulb, including the greater portion of the bulb neck, is preferably formed with a light frost. As a result, the light rays transmitted through the top portion 13 are somewhat diffused.

Mounted within the bulb 10 symmetrically about the focal point or optical center of the reflecting surface 15 is an electric energy translation element or filament 16 of a refractory metal, preferably tungsten. This filament preferably comprises a coil formed into a V-shape with the plane of the V extending transversely of the longitudinal axis of the bulb. The filament is of relatively high wattage such as, for instance, 300 watts or higher, and is supported at its ends by a pair of leading-in wires 17, 18 preferably of nickel. These leading-in wires are sealed in the press portion 20 of an inwardly extending stem 19 and are soldered or otherwise secured to the base shell 21 and eyelet 22. The V-shaped filament is further supported at its mid-point or apex by a support wire 23 the lower end of which is embedded in a button 24 formed at the upper end of a glass arbor 25 extending upwardly from the stem press 20.

Mounted within the neck 11 of the bulb between the filament 16 and stem press 20 is a heat protective device according to the invention. This heat protective device comprises a refractory disc 26 of ceramic or other suitable material and a substantially cylindrical metal shield or wire screen member 27 disposed substantially concentrically within the bulb neck 11. The disc 26 is preferably made of a ceramic material commercially known as "Alsimax," but it may be made of any ceramic possessing fair strength and

characterized by freedom from moisture, such as porcelain, lava or sillimanite. "Alsimag" is useful for the reason that it will withstand relatively high temperatures without giving up harmful impurities, and furthermore because it is white in appearance, thus possessing light reflecting properties. The ceramic disc 26 is disposed concentrically within the bulb neck just above the button 24 on the glass arbor 25, and is supported in such position by two support wires 28, 29 and also by the filament support wire 23. The disc support wires 28, 29 are embedded at one end in the glass button 24 and extend laterally therefrom. At their outer ends, the said disc support wires are bent around the edge or periphery of the ceramic disc, as shown at 30, so as to rigidly clamp the same. The filament support wire 23 is formed with a laterally extending bent portion 31 (Fig. 2) which likewise clamps around the edge of the ceramic disc 26. The three supports 23, 28 and 29 for the disc 26 are arranged approximately 120° apart so as to support the disc at equally spaced points around its periphery. To prevent rotation of the disc, the periphery thereof is provided with notches 32 into which the support wires 23, 28 and 29 extend. The disc 26 is further provided with a pair of openings 33, 33 through which the leading-in wires 17, 18 extend. The cylindrical shield or wire screen member 27 surrounds the ceramic disc 26 and extends from a point just below the filament 16 to a point opposite the stem press or thereabouts. This screen member is secured, at a point intermediate its length, to the periphery of the ceramic disc 26. For this purpose, the inner surface of the screen member 27 is formed with an annular groove 34 which receives the edge of the ceramic disc 26. The wire screen member is made of suitable material, such as nickel wire, and with suitably sized mesh openings, such as, for instance, 20 per inch. The cylindrical screen member is formed from a flat screen which is first provided with the groove 34. Then the flat screen is wrapped around the ceramic disc 26 so that the edge of the disc enters the groove 34 in the wire screen, and the overlapping ends of the wire screen spot-welded or otherwise secured together so as to maintain the wire screen in its cylindrical shape as well as in place on the disc. The ceramic disc 26 serves primarily as a heat deflector to shield the bulb neck 11, glass stem 20, the lamp base 12, and even the associated lamp socket, from the heat radiations of the filament when the lamp is burned in a base-up position. Furthermore, the disc 26, being made of a ceramic material white in appearance, also serves as a light reflector to redirect forwardly into the beam all those rays from the filament which would otherwise pass out through the bulb neck and be lost. In this manner, undesirable back-light through the uncoated portion of the bulb neck is eliminated. The metal screen member 27 serves to protect the bulb neck 11 and adjacent portions 35 of the bulb side wall from excessive localization of heat and possible cracking of the glass which otherwise might result when the lamp is burned in a base-up position. The wire screen diffuses or breaks up the hot gas convection currents within the bulb and effectively maintains the neck and adjacent side wall portions 35 of the bulb at permissible temperatures. Without the wire screen member, the heat rays from the filament would be deflected by the ceramic disc 26 against the bulb neck 11 at points closely adjacent the pe-

riphery of the disc, thus causing intense localized heating of the glass at such points. Such an intense localized heating would cause the reflecting coating 16 to burn at such points and so present an unsightly appearance, or it may result in the cracking of the glass. Consequently, the wire screen member must be employed in conjunction with, and in addition to, the ceramic disc 26 in order to obtain effective protection of both the bulb and the reflecting coating from the heat radiations. Because of such effective protection, it is therefore possible to employ a relatively small sized bulb for lamps of relatively high wattage.

To enable the cylindrical wire screen member 27 and the refractory disc 26 to effectively perform their heat protective functions, they must be of adequate size in relation to the bulb neck and the lamp filament. The disc 26 should be made of a diameter approximating that of the bulb neck so that it extends across substantially the entire space within the bulb neck and substantially closes off the same, but with its periphery slightly spaced from the inner surface of the bulb neck. The cylindrical wire screen member 27 should be of such a diameter that, if extended, it would enclose the filament 16 as well as the leading-in wires 17, 18 and support wire 23. In other words, the cylindrical screen member, mounted concentrically within the bulb neck, should be of such a diameter that the lateral location of any given element of its surface will lie intermediate the centrally mounted filament and the bulb neck wall. In addition, the wire screen member 27 should be of sufficient length, i. e., should extend a sufficient distance towards the filament 16 to more or less shield from the filament the relatively sharp-curved joining portions 35 of the bulb joining the bulb neck and side wall portions 11 and 14, respectively. Such reversely curved joining portions are of little assistance in the production of the resultant light beam so that the interposition of the wire screen between the filament and such relatively ineffective joining portions 35 does not cause any appreciable loss in the intensity of the projected beam. With the particular arrangement shown in the drawings, the wire screen member 27 and ceramic disc 26 together function as a heat protective device or shield not only when the lamp is burned in a vertical base-up position, but even when the lamp is tilted to a position at an appreciable angle from vertical base-up position, such as 45° or thereabouts.

In addition to its function as a heat protecting device, the wire screen member 27 also serves as an effective blackening collector when the lamp is burned in a position approximating a base-up position. The wire screen collects a considerable percentage of the filament particles vaporized off the filament during operation which might otherwise be deposited on the bulb wall. Thus, blackening of the bulb is materially reduced with consequent maintenance of lamp efficiency for a longer period of time.

Although I prefer to employ a wire screen for the purpose of protecting the bulb neck and adjacent portions of the bulb side wall from the heat radiated by the filament, other suitable means may be employed if desired. Thus a solid metal shield in the shape of a cup may be mounted on the ceramic disc 26 so as to face the filament 16. In such case, the metal cup is preferably made of a material having a surface which will reflect light so that the metal cup has the

additional function of a light reflector. While such a metal cup is effective in preventing overheating and cracking of the glass bulb, it does not diffuse the hot gases within the bulb or collect the blackening particles as effectively as does the wire screen member 21.

What I claim as new and desire to secure by Letters Patent of the United States is:

1. An electric incandescent lamp comprising a sealed glass bulb containing a gas filling and having a neck portion, an electric energy translation element of relatively high wattage mounted within said bulb in relatively close relation to said neck portion and normally causing overheating of said neck portion, and a heat protective device mounted within said bulb to deflect and diffuse the hot gas currents therein, said device comprising a disc of refractory material mounted centrally within said neck portion and extending transversely thereof, said disc deflecting the hot gas currents away from said neck portion, and a cylindrical wire screen member disposed substantially concentrically within said bulb neck and extending between said disc and said translation element, said wire screen member being arranged to diffuse the hot gas currents within said neck portion and prevent over-heating thereof.
2. A reflecting electric incandescent lamp comprising a sealed glass bulb containing a gas filling and having a side wall portion and a neck portion, a continuous reflecting coating on the inner surface of said side wall and neck portions, an electric energy translation element of relatively high wattage mounted within said bulb in relatively close relation to said neck portion and normally causing overheating of said neck and adjacent side wall portions, and a heat protective device mounted within said bulb to deflect and diffuse the hot gas currents therein, said device comprising a disc of refractory material mounted centrally within said neck portion and extending transversely thereof, said disc deflecting the hot gas currents away from said neck portion, and a cylindrical wire screen member disposed substantially concentrically within said bulb neck and extending between said disc and said translation element, said wire screen member being arranged to diffuse the hot gas currents within said neck portion and prevent over-heating of the said neck portion and the reflecting coating thereon.
3. A reflecting electric incandescent lamp comprising a sealed glass bulb having a side wall portion and a neck portion, a continuous reflecting coating on the inner surface of said side wall and neck portions, an electric energy translation element of relatively high wattage mounted within said bulb in relatively close relation to said neck portion and normally causing overheating of said neck and adjacent side wall portions, and a heat protective device mounted within said bulb to deflect and diffuse the hot gas currents therein, said device comprising a

reflecting disc of refractory material mounted centrally within said neck portion and substantially closing off the same, and a cylindrical wire screen member disposed substantially concentrically within said bulb neck and extending between said disc and said translation element, said cylindrical wire screen member being of approximately the same diameter as said disc with its upper edge located a relatively slight distance below said translation element.

4. A reflecting electric incandescent lamp comprising a sealed glass bulb containing a gas filling and having a side wall portion and a neck portion, a continuous reflecting coating on the inner surface of said side wall and neck portions, an electric energy translation element of relatively high wattage mounted within said bulb in relatively close relation to said neck portion and normally causing overheating of said neck and adjacent side wall portions, and a heat protective device mounted within said bulb to deflect and diffuse the hot gas currents therein, said device comprising a disc of refractory material mounted centrally within said neck portion and extending transversely thereof, said disc deflecting the hot gas currents away from said neck portion, and a cylindrical wire screen member surrounding said disc and secured to the periphery thereof, said wire screen member extending from said disc towards said translation element, the upper edge of said wire screen member being located a relatively slight distance below said translation element.

5. A reflecting electric incandescent lamp comprising a sealed glass bulb containing a gas filling and having a side wall portion, a neck portion, and an inwardly projecting stem in said neck portion, a continuous reflecting coating on the inner surface of said side wall and neck portions, a glass arbor extending longitudinally of said bulb from the inner end of said stem, an electric energy translation element of relatively high wattage mounted within said bulb in relatively close relation to said neck portion and normally causing overheating of said neck and adjacent side wall portions, and a heat protective device mounted within said bulb to deflect and diffuse the hot gas currents therein, said device comprising a reflecting disc of refractory material mounted centrally within said neck portion and substantially closing off the same, said disc being supported by a plurality of support wires embedded in said glass arbor, and a cylindrical wire screen member disposed substantially concentrically within said bulb neck and extending between said disc and said translation element, said cylindrical wire screen member being of approximately the same diameter as said disc and being secured to the periphery thereof, the upper edge of said wire screen member terminating a relatively slight distance below said translation element.

IRVING H. VAN HORN.

CERTIFICATE OF CORRECTION.

Patent No. 2,232,816.

February 25, 1941.

IRVING H. VAN HORN.

It is hereby certified that error appears in the printed specification of the above numbered patent requiring correction as follows: Page 3, first column, line 54, claim 3, after the word "bulb" insert --containing a gas filling and--; and that the said Letters Patent should be read with this correction therein that the same may conform to the record of the case in the Patent Office.

Signed and sealed this 25th day of March, A. D. 1941.

Henry Van Arsdale,

Acting Commissioner of Patents.
